FOOTWEAR SOLE

William Virgil Wakeland, Rock Island, Ill., assignor to
The Servus Rubber Company, Rock Island, Ill., a corporation of Illinois

Filed July 6, 1965, Ser. No. 86,039

Term of patent 7 years

(Cl. D7—5)

FIGURE 1 is a bottom plan view of a footwear sole, showing my new design, the side opposite being plain and unornamented; and

FIG. 2 is a side elevational view thereof, the side opposite being substantially similar thereto.

I claim:

The ornamental design for a footwear sole, substantially as shown and described.
